REGENERATIVE FURNACE AND MEANS FOR
MEASURING THE TEMPERATURE THERE-
OFLewis Rumford, II, Wilmington, Del., assignor
to United States Steel Corporation, New York,
N. Y., a corporation of New Jersey

Application December 24, 1936, Serial No. 117,665

4 Claims. (Cl. 73—343)

This invention relates to regenerative furnaces and more particularly to means for measuring the temperatures attained in said furnaces during operation of the same.

5 In order to operate an open hearth furnace efficiently some means for determining the checker chamber temperatures must be provided so that both ends of the furnace may be properly balanced as to temperatures and so that overheating of the checker chambers may not occur. Otherwise the reversing of the furnace manually 10 or automatically is performed purely by guess-work, which at best is unreliable and unsatisfactory.

15 One of the objects of the present invention is to provide means to obtain a continuous record of checker chamber temperatures to facilitate the operation of a regenerative furnace and to obtain thereby the maximum efficiency thereof.

20 Another object is to provide means to determine the temperatures attained by the checker-brick located at the hottest point in the checker chamber during the time the said checker chamber is being heated by outgoing gases and to provide means associated therewith to interrupt or 25 discontinue such temperature measurements while the said checker chamber is cooling down during the passage of incoming gases therethrough. Other objects will be apparent as the invention is more fully disclosed.

30 In accordance with the objects of the present invention I dispose a radiation pyrometer in a position to be sighted through an opening in the checker chamber wall upon the checker brick-work therein at the point where the brick is subjected to the maximum heating effects incident to the passage of heated gases therethrough and provide means for closing automatically the said opening when the furnace is reversed so that no 35 temperature measurements then are made until a following reversal automatically uncovers the said opening. As a specific embodiment of the present invention I preferably employ a shutter and solenoid actuated means for moving the 40 shutter into position to cover and uncover the said opening.

45 Reference in this connection should be made to the single figure of the accompanying drawing wherein I have schematically illustrated the 50 present invention.

55 Referring to the drawing, the regenerative furnace is indicated schematically as comprising a hearth 1 retaining a metal bath 2 and enclosed from the atmosphere by roof 3. The regenerative furnace indicated is the type adapted to be

heated by producer gas. It is customary to preheat both the producer gas and the air admixed therewith for combustion purposes before passing the gas and air into the furnace. This is accomplished by providing two checker chambers 5 at each end of the furnace indicated as A—A' and B—B', chambers A and B serving as preheat chambers for the air and chambers A'—B' serving as preheat chambers for the producer gas. In the position indicated in the drawing chambers A—A' are serving as preheat chamber for the air and producer gas respectively during one heating cycle and chambers B—B' are being heated by the outgoing gases of combustion, the flow of gases being indicated by arrows. 10

15 In accordance with the present invention I dispose radiation pyrometers P1, P2, P3 and P4 in a position to be sighted through suitable openings in the walls of chambers A', A, B and B' respectively upon the top of the checker brick-work 4 located therein and then provide solenoid actuated shutter means S1 and S2 to cover up the openings in chambers A' and B' (the producer gas preheat chambers) when the said chambers are being utilized as preheat chambers 20 but to uncover the openings when the chambers are being utilized as exhaust chambers and are being heated up preparatory to again serving as preheat chambers. 25

30 In the normal reversing procedure, the manually operating and the automatically operating reversing means provided functions to simultaneously reverse valves V1 and V2 into the dotted position indicated and then back to the solid line position indicated, the period of reversal depending upon the temperatures attained in the checker chambers at each heating up cycle. Reversal of valves V1 and V2 is accomplished by 35 hydraulic rams R (indicated schematically).

40 To avoid danger of explosion by the escape of producer gas through the openings through which pyrometers P1 and P4 are sighted or by the entrance of air into the chamber through these openings, it is essential that the solenoid actuated means S1 and S2 covering and uncovering 45 these openings should act positively upon the actuation of valve V2.

I therefore dispose an extension rod 5 upon the hydraulic ram R actuating valve V2 in such position as to strike spring contacts 6—6' at opposite strokes of the ram causing them to make electrical contact with contacts 7—7'. Numeral 5' indicates the position taken by rod 5 at the other end of the stroke of ram R. 50

55 Upon the closing of either contacts 6—6' with

- 1—1' solenoid S1 or S2 (as the case may be) is energized thereby operating to open the shutter and uncovering the opening through which pyrometer P4 (or P1 as the case may be) is sighted.
- 5 In the position shown in the drawing the checker chambers to the left (A—A') are operating on what is known as the preheat or ingoing cycle and chambers B—B' (to the right) are operating on the heating up or outgoing gas cycle. The arrangement indicated permits solenoid S2 to be energized and pyrometer P4 to record the temperatures attained whereas solenoid S1 is de-energized and pyrometer P1 is prevented from recording. Pyrometers P2 and P3, however,
- 10 record the temperatures obtained in chambers A and B respectively. Upon reversal solenoid S1 is energized and solenoid S2 de-energized and pyrometer P1 becomes recording whereas pyrometer P4 does not record.
- 15
- 20 Having described the present invention and given one specific embodiment of the same, it is apparent that modifications and adaptations may be made thereof and all such are contemplated as may fall within the scope of the accompanying claims:

What I claim is:

1. A regenerative furnace, checker chambers adapted to preheat the air and gaseous fuel utilized in said furnace, each chamber being provided with an opening in one wall thereof, a radiation pyrometer device closing said opening, shutter means disposed in said opening intermediate said pyrometer and the interior of said chamber, and solenoid actuated means to move said shutter means to open and closed positions and means actuated upon reversal of said furnace to energize and de-energize the said solenoid means.
2. A regenerative furnace including checker chambers disposed adjacent each end of said furnace and provided with means to reverse the fuel and air supply to the furnace thereby to alternately heat up and cool down said chambers by the passage of outgoing gases of combustion and ingoing fuel and air therethrough respectively, each checker chamber being provided with means to determine the temperatures attained by the checker brickwork in said checker chambers during the heating up cycle, said means including an opening extending through the wall of said chamber adjacent the top thereof, a radiation pyrometer closing said opening from the atmosphere, a shutter element disposed in said opening intermediate the pyrometer device and the interior of the chamber, solenoid actuated means to move the shutter to shut and open posi-

tion, and means actuated by said furnace reversing means to energize and de-energize said solenoid means upon operation of said reversing means, said energization and de-energization of the solenoid means being adapted to open the shutter element in the opening during the heating up period for the chamber and to close the shutter during the period of cooling down.

3. A regenerative furnace including checker chambers disposed adjacent each end of the furnace for the preheating of air and gaseous fuel for the furnace means to reverse the said furnace, to alternately pass the gaseous products of combustion from the furnace through the said check chambers, an opening through the wall of each checker chamber adjacent the top thereof, a radiation pyrometer device closing each opening, a shutter element located in each opening, solenoid actuated means to position each shutter to block off radiation passing to the pyrometer from said chamber, and means actuated by said furnace reversing means to energize each solenoid actuated means to thereby position said shutter in blocking position during the cooling period and in unblocking position during the heating up period of the checker chamber.

4. A regenerative furnace of the gaseous fuel type, a pair of checker chambers disposed adjacent each end of said furnace and communicating therewith, means to pass air and gaseous fuel through one pair of said chambers while the opposite pair are being heated up by the passage of gaseous products of combustion from the furnace therethrough, means to reverse the flow of said gases to thereby preheat said air and gaseous fuel before entering into said furnace, means to determine the temperatures of said chambers, said means including an opening through a wall of each checker chamber and a radiation pyrometer device closing each of said openings, shutter means in each opening of the chambers through which gaseous fuel passes and adopted in one position to close off one of said radiation pyrometer devices from radiation emitted from one of said chambers and in a second position to permit said radiation to pass to said pyrometer device, solenoid actuated means to operate each of said shutter means into said two positions, and means actuated automatically by said reversing means to energize the said solenoid actuated means operating the shutter means to thereby close off radiations passing to said pyrometer devices during the cooling down period and to operate the shutter means during heating up period.

LEWIS RUMFORD, II.
